CARTON

William A. Ringler, Wayne, Pa., assignor to
National Folding Box Company, New Haven,
Conn., a corporation of New Jersey

Original application June 24, 1936, Serial No.
86,917. Divided and this application July 1,
1939, Serial No. 282,479

11 Claims. (Cl. 229—6)

This invention relates to cartons, and more particularly to a carton for the packaging of radio tubes, electric light bulbs and similar articles, which require testing to determine whether they are in good, serviceable condition before delivery to the customer. This application is a division of my copending application Serial No. 86,917, filed June 24, 1936, which issued into Patent No. 2,164,346 on July 4, 1939.

Customers generally require an actual test of such articles as radio tubes and electric light bulbs to determine whether they are in serviceable condition before accepting delivery of same. Such test requires that the test end of the article be inserted in a suitable electric socket to determine whether the article properly responds to the current or energy waves to which it is subjected. Irresponsible dealers and bootleggers have heretofore taken advantage of this requirement by actually removing the article originally packed by the manufacturer in the carton, and inserting a used or inferior article in its place. Legitimate manufacturers naturally desire to safeguard their product and their customers against such operations, and to this end this invention is directed.

An object of this invention is to provide a carton especially adapted for the packaging of radio tubes, electric light bulbs, and similar articles, which permits full and complete test of the article before use, but which is so constructed as to prevent unauthorized removal of the original article from the carton.

Another object of this invention is to provide an improved carton for articles to be tested prior to use, which permits a limited movement of the article within the carton for purpose of test, but which will effectively prevent unauthorized removal of the article therefrom, thus insuring delivery of the original article to the customer.

Still another object of this invention is to provide an improved carton for articles to be tested prior to sale, which fully protects the article from injury resulting from external shock, which permits quick manipulation of the article for purpose of test and yet positively prevents unauthorized removal of the article therefrom, which carton can be inexpensively and economically manufactured, assembled and packed substantially entirely by automatic machinery, and which is susceptible of being formed into a variety of attractive designs and patterns.

Other objects of this invention will become apparent as the disclosure proceeds.

Although the novel features which are believed

to be characteristic of this invention will be particularly pointed out in the claims appended hereto, the invention itself, as to its objects and advantages, and the manner in which it may be carried out, may be better understood by referring to the following description taken in connection with the accompanying drawing forming a part thereof, in which:

Fig. 1 shows an extended blank from which the outer tubular member of the container may be made;

Fig. 2 shows a blank from which the inner sleeve may be made, which sleeve is adapted to be associated with the outer tubular member assembled from the blank shown in Fig. 1;

Fig. 3 is a perspective view of the sleeve-forming blank shown in Fig. 2 in the process of assembly about a corrugated protective shell which surrounds the article;

Fig. 4 is a perspective view of the tube-forming blank shown in Fig. 1 in the process of being assembled about the article-containing shell and sliding sleeve;

Fig. 5 is a perspective view of the carton as it appears prior to sealing, the tube-protecting shell and sliding sleeve being shown in test position;

Fig. 6 is a perspective view of the carton in the process of being closed and sealed; and

Fig. 7 is a perspective view of the fully assembled carton.

Similar reference characters refer to similar parts throughout the several views of the drawing and the specification.

The carton forming the subject matter of this invention is particularly designed for the packaging of radio tubes, electric light bulbs, and similar articles requiring test before use, which article will be hereinafter designated T. The carton comprises generally an outer tubular member A which contains an inner sliding member B. The inner sliding member supports the article T which may be encased in a protective shell C. Means are provided to permit limited sliding movement of the inner sliding member within the outer tubular member so that the article can be tested when desired. The carton is so constructed, however, that the article cannot be removed without mutilating or destroying the carton or otherwise leaving visible evidence that the carton has been tampered with and access to the article originally packed therein obtained.

Referring more particularly to Figs. 1, 4, 5 and 6, the outer tubular member A may be formed from the blank shown in Fig. 1, com-

prising side wall-forming sections 1, 2, 3 and 4, defined by the longitudinally extending score line 6. A closure section 5 hinged to the side wall section 4 along the score line 6 is arranged to overlap the side wall section 1 to form a closed tubular outer member. The manner in which the outer tubular member is closed and sealed will be discussed more in detail hereinafter.

Fig. 2 shows a blank from which the inner slideable member B may be formed, comprising a bottom wall section 11 and a top wall section 12 connected by a side wall section 10 along the score lines 18. The bottom section 11 is provided with an opening 19 through which the test end *p* of the article T may project. The top wall section 12 is provided with a suitably shaped opening 20 which serves to center the article within the inner member. Side wall portions 13 and 16, hinged respectively to the bottom wall section 11 and the top wall section 12 along the score lines 18, are provided with hook portions 21 which may be interlocked together when the article has been placed therein.

In packaging the carton, the article T may be first telescoped into the corrugated shell C comprising the surrounding side walls 30. The shell C serves as a cushion to protect the fragile article against injury from shock. The inner member or sleeve B is then wrapped around the article T and the protective shell C by first placing the test end of the article in supporting position on the bottom section 11, with test prongs *p* projecting through the opening 19. The top wall section 12 is then placed over the top end of the article, the opening 20 serving to center the article in position. The side wall-forming portions 13 and 16 are then swung into position and connected by means of hook portions 21 and 22 so that the side wall portions 13 and 16 form a fully assembled side wall section positioned opposite to the side wall section 10.

The outer tubular member formed from the blank shown in Fig. 1 is provided with a cut-out recess 60 in the side wall section 1, preferably extending to the free edge thereof. A tab portion 62 extending from the free edge of the overlapping section 5 may also be provided. It will be noted that a plurality of blanks shown in Fig. 1 may be cut from a paperboard sheet without waste of material, due to the fact that the material cut out from section 1 to form the recess 60 forms the tab portion 62 extending from section 5 of the adjacent blank.

The outer tubular member, while in blank form, is assembled around the assembled inner sliding member in the manner shown in Fig. 4. A projection associated with the inner sliding member, such as the hook portions 21 extending from either the side wall portion 13 or 16 of the inner member, extends through the slot 60 so that this projection may be moved into abutment against the top edge 60b or bottom edge 60a of the side wall section 1, as shown in Fig. 5. The overlapping section 5 is then positioned over the side wall section 1 so as to cover and conceal the projection, such as the hook portion 21. The projecting tab 62 may be inserted through a corresponding slit 63 extending along a portion of the score line 6 which joins the sections 1 and 2. The outer tubular member may be sealed in closed position by the application of adhesive or eyelets 29 to the overlapped sections 5 and 1 at each end there-

of, as more fully shown in Fig. 7. The tab portion 62 may be of such length as to prevent the insertion of a cutting tool between the overlapped sections 5 and 1 to effect mutilation of the hook portion 21 which locks the inner sliding member within the outer tubular member. The tab portion 62 thus acts as a shield to prevent unauthorized mutilation of the carton. In addition, the tab portion 62 serves to hold the outer tubular member in a relatively fixed tubular shape while the securing eyelets 29 are being applied.

It will be noted that when the inner sliding member is moved into test position, the lower edge portion 60a will abut against the inside face of the projection or neck portion which joins the hook portion 21 to the side wall portion 16, as at 21a (see Fig. 5). The inner sliding member cannot be further ejected. When in the ejected position above described the leg portions 17 may be swung outwardly to permit free insertion of the test prongs *p* into a suitable socket. When the inner member is completely housed within the outer member during shipment and storage, the upper edge portion 60b of the recess 60 will abut against the outside face of the neck of the hook portion 21, as at 21b. Thus the amount of sliding movement of the inner member can be determined and fixed by the space between the opposite edge portions 60a and 60b of the recess 60. The hook portion 21 and associated recess 60 is concealed from view and inaccessible to unauthorized tampering by the side wall section 5 which completely overlies the same. The recess portion 60 may be of any desired shape but preferably the edge portions 60a and 60b thereof extend substantially transversely across the side wall section 1 and at right angles to the free edge thereof so as to provide a positive non-slip stop for the sliding inner member. If desired, a projecting nose portion 61 extending inwardly toward the recess may be provided to assist in preventing dislocation of the neck of the hook portion 21 from its seated position in said recess 60.

The carton herein described provides a highly satisfactory and serviceable packing medium for radio tubes, electric light bulbs, and like articles which must be protected against damage and injury during shipment and storage and from unauthorized pilfering of the original contents. The inner member slides within the outer tubular member smoothly and evenly with just sufficient friction to prevent the article from being ejected by jars into a test position, but requiring only a slight pressure on the article T or on the inner sliding member to effect ejection of the test portion *p* of the article for unobstructed testing. The leg portions 17 serve to support the inner sliding member in housed position within the outer member when the carton is placed on a supporting surface, such as a shelf. The leg portions 17 freely swing outwardly so as to be completely out of the way when the test of the article is being made. The leg portions 15 at the other end of the sliding inner member support the head end of the article away from the surface on which the carton rests, should the carton be placed on the supporting surface in an upside down position. The cartons herein disclosed can be economically made with a minimum of paperboard material and can be assembled and packed automatically and substantially entirely without hand operation. The cartons are so constructed that the

original articles packed therein cannot be removed therefrom without first mutilating or destroying the material from which the carton is made, so as to make visibly apparent that access to the contents has been made. The customer, whom a legitimate manufacturer desires to protect, can be warned not to accept from any dealer a packaged article of which the carton bears evidence of mutilation. Thus, the manufacturer as well as the user is assured of obtaining the article originally packed in the carton in good and servicable condition.

While certain novel features of the invention have been disclosed and are pointed out in the annexed claims, it will be understood that various omissions, substitutions and changes may be made by those skilled in the art without departing from the spirit of the invention.

What is claimed is:

1. A carton for a radio tube and the like including, a four-sided outer tubular member formed by at least five hingedly connected side wall forming panel sections, an inner tube-supporting member telescoping within said outer member, one of the panel sections of the outer member presenting a free vertical edge exteriorly overlapped and covered by an adjacent panel section, said inner panel section having spacer cuts extending transversely from the free edge thereof forming spaced abutments and providing space therebetween for the reception of a portion associated with said inner member thereby permitting limited telescoping movement only of said inner member within the outer member, the portion of said inner member movable between said abutment edges being covered by an overlying panel section of the outer member sealed to an adjacent panel section.

2. A carton for radio tubes and the like including, a four-sided outer tubular member formed by at least five hingedly connected side wall forming panel sections, and an inner tube-supporting member adapted to telescope within said outer member, said inner member having end wall portions and a side wall portion comprising a pair of connecting flaps hinged to said end wall portions, spaced transversely extending cuts forming spaced abutment edges in one panel section adapted to be engaged by one of the flaps of said inner member permitting limited telescopic movement of said inner member within the outer member, said outer member having an overlying side wall section fixed to an adjacent section of said outer member covering said flap and abutment edges so that the same cannot be removed or detached to effectuate removal of the tube without leaving telltale evidence of tampering.

3. A carton for radio tubes and the like including, a four-sided outer tubular member having at least five hingedly connected side wall panels forming a container of generally rectangular form, and an inner tube-supporting member adapted to telescope within said outer member, said inner member having end wall sections and a side wall section comprising a pair of connecting flaps hinged to said end wall sections, said outer member having an opening in a side wall panel thereof defined by spaced transversely extending cuts defining spaced transversely extending edges, said edges providing abutments for one of the connecting flaps of said inner member projecting into said opening thereby limiting the telescoping movement of the inner member within the outer member, one of said side wall panels overlying said opening and abutment edges, and

means for sealing said last named side wall panel to an adjacent panel to retain the outer member in fixed tubular position.

4. A container for radio tubes and the like including, a four-sided outer tubular member having at least five hingedly connected side wall-forming sections, and an inner tube-supporting member adapted to telescope within said outer member, one of the panel sections of the outer member presenting a free vertical edge exteriorly overlapped and covered by an adjacent panel section, said inner panel section having a notch cut therein extending transversely inwardly from the free edge thereof providing a guide opening adapted to receive an abutment portion associated with said inner member so as to limit the telescoping movement of said inner member within the outer member, and means for permanently sealing said overlying panel section in fixed position to said adjacent inner panel section.

5. A container for radio tubes and the like including, a four-sided tubular outer member comprising at least five hingedly connected panel sections, an inner member adapted to contain a tube telescoping within said outer member, one of the panel sections of the outer member presenting a free vertical edge exteriorly overlapped and covered by an adjacent panel section, said inner member having a guide opening defined by spaced abutment edges extending transversely from the free edge thereof, said inner member having a portion thereof projecting into said opening thereby limiting the telescoping movement of said inner member within the outer member, said outer member having a panel section thereof overlying said guide opening and permanently fixed to an adjacent panel section so as to prevent unauthorized release of said portion of the inner member from said guide opening without leaving visible evidence of tampering.

6. A container for radio tubes and the like including, an article-supporting member enclosing said tube, and a four-sided outer tubular member formed from at least five hingedly connected side wall forming panel sections enclosing said article-supporting member, said article-supporting member including end wall sections and a side wall section comprising a pair of connecting flaps hinged to said end wall sections, said outer tubular member having a guide opening in one of its panel sections which receives one of the connecting flaps of said inner member cooperating to limit the sliding movement of said inner member in said outer tubular member, said guide opening extending from a side edge of said panel section transversely inwardly thereof for a substantial distance.

7. A package for radio tubes and the like including, an inner protective shell enclosing the tube, an inner member surrounding said protective shell, said inner member including spaced end wall sections and a side wall section comprising a pair of connecting flaps hinged to said end wall sections and a four-sided outer member formed from at least five hingedly connected side wall forming panel sections enclosing said inner member, said outer member having a guide opening in a panel section thereof receiving one of the connecting flaps of said inner member to limit and define the sliding movement thereof, said guide opening extending from a side edge of said panel section transversely inwardly thereof for a substantial distance.

8. A container for radio tubes and the like including, a four-sided outer member including at least five hingedly connected side wall panels, an inner member adapted to contain a tube telescoping within said outer member, said inner member including end wall sections and side wall sections connecting said end wall sections, one of said end wall sections having an opening through which the test end of the tube may be projected for test purposes, one of said side wall sections comprising a pair of side wall flaps hingedly connected to opposite end sections, said side wall flaps having hook portions for connecting said flaps together, one of said hook portions on said inner member cooperating with spaced abutments formed in a side wall panel of the outer member to define and limit the telescoping movement of the test end of the tube, one of said side wall panels overlying the side wall panel provided with said spaced abutments, said overlying side wall panel having a tab projecting from the free side edge thereof extending into a receiving slit cut in the adjacent side wall panel.

9. A container for radio tubes and the like including, a four-sided outer member including at least five hingedly connected side wall panels, an inner member adapted to contain a tube telescoping within said outer member, said inner member including end wall sections and side wall sections connecting said end wall sections, one of said end wall sections having an opening through which the test end of the tube may be projected for test purposes, one of said side wall sections comprising a pair of side wall flaps hingedly connected to opposite end sections, said side wall flaps having hook portions for connecting said flaps together, and an aperture in a side wall panel of said outer member adapted to cooperate with one of said hook portions on said inner member to define and limit the telescoping movement of the test end of the tube, said apertured side wall panel being closed by an overlying side wall panel, said overlying side wall panel having a tab projecting from the free side edge thereof extending into a receiving slit cut in the adjacent side wall panel.

10. A container for radio tubes and the like including, an outer member formed by enclosing side wall panels, an inner member adapted to contain a tube telescoping within said outer member, said inner member including end wall sections and side wall sections connecting said end wall sections, one of said end wall sections having an opening through which the test end of the tube may be projected for test purposes, one of said side wall sections comprising a pair of side wall flaps hingedly connected to opposite end sections, said side wall flaps having hook portions for connecting said flaps together, one of said hook portions projecting outwardly into an opening cut in one of said side wall panels and cooperating with spaced transversely ex-

tending abutment edges of substantial length defining said opening to limit the telescoping movement of the test end of the tube.

11. A container for radio tubes including, an outer tubular sleeve formed from a single blank of paperboard material comprising four enclosing side wall panels hingedly connected together along parallel extending corner fold lines presenting a sleeve of generally square cross-section, said side wall panels having free ends and presenting square inside corner faces, an inner tube-supporting and enclosing member formed from a single blank of paperboard material shaped to snugly telescope within said outer sleeve, said inner member including two spaced tube-supporting platforms having a generally square contour, one of said platforms having a centrally disposed aperture therein through which the prong portions of the tube may extend and the other of said platforms having a centrally disposed aperture therein for centering the adjacent end of the tube within said inner member, a rectangular side wall section hingedly connected to said spaced platforms along one side of said inner member and presenting substantially parallel side edges arranged to snugly and frictionally seat against the inside corner faces of said side wall panels, a side wall flap hingedly connected to each of said platforms opposite said side wall section first named, said side wall flaps having hook portions whereby said flaps may be separately connected to form a side wall section presenting substantially parallel extending side edges corresponding in length and width to the side wall section first named, said second side wall section formed by said connected flaps having the side edges thereof arranged to snugly and frictionally seat against the adjacent inside corner faces of said side wall panels, and a pair of outturned guide flaps having square cut vertical edges hingedly connected to the other opposite side edges of each of said platforms providing end supports for said inner sleeve, the square cut edges of said guide flaps forming a substantially straightline continuation of the adjacent side edges of said side wall sections when said inner member is positioned within said outer member, the combined length of each side wall section and the outturned guide flaps at each end thereof being approximately the length of the adjacent free end side wall panel of the outer sleeve, said inner member being so dimensioned that when positioned within the outer sleeve the outside faces of said outturned flaps will snugly seat against the inside faces of the adjacent side wall panel and the side edges of said side wall sections and guide flaps will frictionally engage the adjacent corner faces formed by said side wall panels so that the inner member is frictionally retained in said outer sleeve.

WILLIAM A. RINGLER.
